FOAM PRODUCER FOR CLEANING APPARATUS

Filed July 27, 1950

UNITED STATES PATENT OFFICE

2,674,444

FOAM PRODUCER FOR CLEANING APPARATUS

James L. Chatterton, Dayton, Ohio

Application July 27, 1950, Serial No. 176,151

5 Claims. (Cl. 261—121)

1 This invention relates to cleaning apparatus, and particularly to apparatus for producing a suds and delivering the same through a brush for utilizing the cleansing action of the suds aided by the scrubbing action of the brush. Even more particularly, the invention relates to apparatus for producing an aerated suds or foam in such a manner that the foam can be delivered to a place of cleansing action as a foam and thereby eliminate the disadvantages inherent with the utilization of liquids for cleansing action.

In this invention an aqueous foam or suds is produced in the apparatus and is delivered under pressure as a foam through a scrubbing brush in such a manner that the wetting action produced by the liquid in the foam is held to a minimum so that the aqueous foam will not cause shrinkage of normal fabrics, nor will they be unduly wet by the liquid content of the foam.

Detergent cleaners are well known on the commercial market, many of which cleaners produce their cleansing action by a foam created in the detergent, but it is conventional practice to have the detergent carried in a liquid vehicle that is highly volatile in nature to avoid undue wetting of the fabric or article being cleansed, and to provide for rapid evaporation of the liquid carrier.

It is an object of this invention to provide an apparatus that is capable of producing a high volume of aerated suds or foam that will contain a minimum amount of liquid in the foam and is particularly adaptable for producing aerated suds or foam from an aqueous solution.

While the apparatus is particularly well adapted for producing foam from an aqueous solution, yet it is not limited to such use, as other foam detergents can be used in the apparatus without in any way affecting the operation of the apparatus.

It is an object of the invention to provide an apparatus that can be used in the manner heretofore disclosed, which will contain no moving parts, and thereby obtain an apparatus that is trouble free, is low cost in manufacture, and is inexpensive to maintain.

It is still another object of the invention to provide an apparatus in accordance with the foregoing object wherein a gaseous medium under pressure is used for producing an aerating action in the detergent solution in the apparatus and thereby produce foaming of the detergent and to use the gaseous medium that causes the foaming action of the detergent as the medium by which the foam or suds so produced is deliv-

2 ered through a flexible conduit to a point of use.

Still another object of the invention is to provide a cleansing apparatus having a dual chamber structure, in one chamber of which liquid detergent is aerated to produce suds or foam which is delivered to the second chamber of the dual chamber arrangement to maintain the suds or foam separate from the liquid from which it was produced and thereby provide for delivery of relatively dry suds or foam from the apparatus, any unstable foam or suds that breaks down being returnable to the body of liquid from which the foam or suds was produced, rather than being delivered from the apparatus.

15 Still another object of the invention is to provide an apparatus in accordance with the foregoing objects wherein a transparent plastic hose is used for delivery of suds or foam from the foam producing apparatus to a suitable place of use so that the operator can at all times inspect the condition of the foam being delivered from the apparatus, and if necessary adjust the apparatus to produce a more stable foam or a greater volume of it to maintain suitable flow through **20** the hose to the desired point of use.

These and other objects will become apparent from the following description and from the drawings in which:

25 Figure 1 is an elevational view of apparatus constructed in accordance with the teaching of this invention;

Figure 2 is a vertical cross sectional view taken through the apparatus of Figure 1;

30 Figure 3 is a horizontal cross sectional view taken substantially along the line 3—3 of Figure 2, which line of section follows substantially the curvature of the bottom wall of the apparatus;

Figure 4 is a cross sectional view of the brush utilized in the invention and is taken along the **35** line 4—4 of Figure 1;

Figure 5 is a cross sectional view taken along line 5—5 of Figure 4; and

Figure 6 is a cross sectional view illustrating a modified construction of the reinforced plastic **40** hose used in this invention.

In this invention, the apparatus consists of a container 10 that is formed of a side wall 13 that is cylindrical in form. Container 10 has a bottom wall 11 that is concave in form and seals against the bottom edge of the cylinder 13. Also, a top wall 12 is provided, which seals against the top edge of the cylinder 13, the top wall being convex in form.

It will be understood that the specific shape **45** of the container can be other than that just

described without departing from the invention, but that the cylindrical and circular shapes are those which give the greatest strength; hence, the desirability of constructing the container in the form illustrated and described.

Within the container 10 there is provided a compartment wall structure generally designated by the numeral 15 that divides the container 10 into three compartments, 16, 17, and 18. The wall structure 15 is in the form of two hollow truncated cones 19 and 20 that have their vertices connected by a conduit or tube 21 for interflow of material between the chambers 17 and 18.

The upper hollow truncated cone 19 of the wall structure 15 is disposed in an inverted position with the base edge 22 of the cone 19 positioned against the top wall 12 of the container 10. Alternately the peripheral edge 22 of the base cone 19 can engage the side wall 13 of the container 10 if desired.

Preferably, the base peripheral edge 22 of the cone 19 can be sealed to the top wall 12 or to the side wall 13 in any suitable manner, such as by soldering operation, or with a resilient seal member.

The sealing of the cone 19 to the top wall 12 or to the side wall 13 of the container 10 provides the closed chamber 18 in the upper portion of the container 10 into which suds or foam is delivered from the lower portion of the container 10 in a manner hereinafter described.

The cone 20 forming the lower end of the wall structure 15 has its base peripheral edge 23 engaging the bottom wall 11 of the container 10. This peripheral edge 23 need not be sealed to the bottom wall 11 of the container 10, as liquid detergent shall move from the compartment 16 into the compartment 17 beneath the peripheral edge 23 of the cone 20.

To provide for more freedom of passage of liquid from the chamber 16 into the chamber 17 when the edge of the cone fits too perfectly on the bottom wall 11, notches 24 and 25, or other suitable openings, are provided in the lower edge of the cone 20 to relieve the restriction.

A vent opening 26 is provided in the inverted cone 19 to provide interflow of gaseous medium between the chamber 18 and the chamber 16 during filling operation of the container 10.

A filling opening 30 is provided in the top wall 12 and has a suitable screw fitting 31 to close the opening 30 and seal it so that gaseous pressure can be delivered into the container 10.

A discharge opening 32 is also provided in the top wall 12 through which stable foam or suds can be discharged into the delivery conduit 33 that is connected to the outlet conduit 34 by means of a releasable clamp 35.

A drain opening 36 is provided in the lower portion of the chamber 16 and is closed by a drain plug 37.

To cause agitation of the detergent solution placed in the container 10, a pipe 40 passes through the top wall 12 of the container 10 and extends downwardly into the container through the tubular connection 21 between the truncated cones 19 and 20 through which air under pressure is delivered into a generally helically arranged conduit 41 positioned in close proximity of the bottom wall 11 of the container 10 and near the outer periphery of the cone 20 at the juncture between the cone 20 and the wall 11.

This distributing tube 41 has a series of holes placed in the upper side thereof so that air under pressure delivered through the pipe 40 will be

exhausted into the liquid contained within the chamber 17.

Air is supplied to the pipe 40 from a supply conduit 42 and is under control of a pressure regulating valve 43, of any conventional construction, to maintain pressure of the air delivered into the conduit 40 at a predetermined value as controlled by the operator through adjustment of the valve 43 by means of the adjusting handle 44.

The pressure gauge 45 indicates the pressure delivered into the pipe 40 and a shut-off valve 46 is provided for completely closing off the air supply to the pipe 40 if desired. The distributing tube 41 is suitably connected to the pipe 40 by a connector 46.

The delivery tube 33 is constructed of a transparent plastic material and has the coiled wire 47 placed in the wall of the tube 33 to reinforce the plastic wall and prevent collapse of the tube 33 due to any sharp bending of the tube.

The delivery tube 33 being constructed of a transparent plastic material permits the operator of the device to have a constant inspection of the flow of suds or foam that is being delivered to the brush 50 placed on the delivery end of the tube 33. Thus, if the operator should determine that the foam is of an unstable variety and a larger amount of liquid is present in the tube than should be there normally, he can adjust the pressure delivered into the container 10 to develop a greater volume of foam or a more stable foam.

Also, the transparency of the tube 33 permits the person for whom work is being done to see the condition of the detergent as it is flowing to the brush 50.

The brush 50 through which the foam or suds is delivered on to the surface being cleansed consists of a hollow body 51 forming a chamber 52 into which the suds or foam is delivered from the tube 33. The chamber 52 is closed by a plate 53 from which rows of bristles 54 project. A series of openings 55 are provided between the rows of bristles 54 for delivery of suds or foam onto the article or surface being cleansed, so that the bristles 54 can perform their scrubbing action immediately at the point of discharge of the cleansing foam onto the article whereat the foam is in its most stable condition, at which time a minimum quantity of liquid is in the foam.

In operation, the container 10 is filled with approximately three gallons of detergent solution through the opening 30, the liquid rising to the level 60 in the container 19, thus leaving chamber 18 free of liquid.

In this invention it is proposed that the detergent solution shall consist of three gallons of water, to which one quart of a detergent has been added.

Air is supplied to the interior of the container through the pipe 40 at a pressure value of approximately one and one-half pounds per square inch, this value having been determined to be sufficient to obtain a high volume of stable suds or foam from the detergent solution used.

Air discharging through the openings in the distributing tube 41 agitates and aerates the detergent solution in the chamber 17 with a violent agitation to produce suds or foam of substantially all of the liquid in the chamber 17.

Since the side walls of the chamber 17 taper upwardly, the foam will rise in the chamber 17 and be delivered through the tube 21 into the upper chamber 18, the foam filling the chamber 18 and spilling out into and through the tube 33.

for discharge through the openings 55 in the brush 50.

Since the tube 33 is the only free discharge for the air that is delivered into the chamber 17, passage of the air through the chamber 18 and into the tube 33 will carry with it the foam and suds within the chamber 18, thus delivering the suds to the brush 50 under pressure but at a relatively low value since the volume of the tube 33 is relatively large and the openings 55 provide a relatively free passage of the air for exhaust from the chamber 18.

As liquid is used from the chamber 17 by the violent sudsing action created in the chamber 17 by delivery of air under pressure into the restricted volume of detergent solution in the chamber 17, liquid from the chamber 16 will supply the chamber 17 through the openings 24 and 25 heretofore described, the liquid level in the chambers 16 and 17 gradually falling correspondingly as the detergent solution is used.

The chamber 18 being above the liquid level 60 provides a chamber into which free suds or foam is delivered which, if stable, will be carried into the delivery tube 33 by a flow of air through the chamber 18 into the tube 33. However, some of the foam produced will not be completely stable, some of it being in the form of bubbles that are either too small or too large for stability.

The unstable foam will break down in the chamber 18 and the liquid formed thereby will drain into the connecting tube 21 between the chambers 18 and 17 and thence into chamber 17 where it will again be acted upon by the air agitation created in the chamber 17. Thus unstable foam and the excess liquid condition created thereby will not be present in the delivery tube 33 for delivery through the brush 50.

Thus, the apparatus of this invention provides for development of a foam with delivery of only stable foam to the surface being cleansed whereby the minimum wetting of the article being cleansed is obtained.

In Figure 6 there is illustrated a slightly modified arrangement of the construction of the delivery tube 33 in which the tube 33a has a coil spring 60 placed internally therein for reenforcement of the tube 33a and to prevent collapse thereof. The spring 60 is prevented from longitudinal movement within the tube 33a by means of a pin 61 extending through the fitting 62 and the end coils 63 of the spring 60.

While the apparatus disclosed and described herein illustrates a preferred form of the invention, yet it will be understood that the apparatus is capable of alteration without departing from the spirit of the invention, and that all modifications that fall within the scope of the appended claims are intended to be included herein.

I claim:

1. Cleaning apparatus that comprises a closed container, a wall structure within said container dividing said container into a plurality of chambers, said chambers comprising a suds receiving and expanding chamber, a suds forming chamber and a liquid storage chamber, said last-mentioned chamber being disposed around said suds receiving and suds forming chambers, means forming a restricted passageway directly connecting said suds receiving and expanding chamber with said suds forming chamber, passageway means of limited liquid flow between said suds forming chamber and said liquid storage chamber, means comprising a conduit extending into said suds forming chamber for delivering a gaseous medium under pressure into said suds forming chamber whereby to form suds therein from liquid in said chamber, and means forming a discharge passage from said suds receiving and expanding chamber.

2. Cleaning apparatus that comprises a closed container, a wall structure within said container dividing said container into a plurality of chambers, said chambers comprising a suds receiving and expanding chamber, a suds forming chamber and a liquid storage chamber, said last-mentioned chamber being disposed around said suds receiving and suds forming chambers, means forming a restricted passageway directly connecting the suds receiving and expanding chamber with the suds forming chamber, passageway means of limited liquid flow between said suds forming chamber and said liquid storage chamber, means in said suds forming chamber positioned at the liquid flow passage for delivering a gaseous medium under pressure into the suds forming chamber whereby to form suds therein from liquid in said chamber, and means forming a discharge passage from said suds receiving and expanding chamber.

3. Cleaning apparatus that comprises a closed container, a wall structure within said container dividing said container into a plurality of chambers, said chambers comprising a suds receiving and expanding chamber, a suds forming chamber and a liquid storage chamber, said last-mentioned chamber being disposed around said suds receiving and suds forming chambers, means forming a restricted passageway directly connecting the suds receiving and expanding chamber with the suds forming chamber, passageway means of limited liquid flow between said suds forming chamber and said liquid storage chamber, means in said suds forming chamber positioned at the liquid flow passage for delivering a gaseous medium under pressure into the suds forming chamber whereby to form suds therein from liquid in said chamber, and means forming a discharge passage from said suds receiving and expanding chamber.

4. Cleaning apparatus comprising; a closed container, dual hollow truncated cone-shaped members in said container interconnected at their vertices and having their base peripheries engaging the walls of said container at opposite ends thereof to provide chamber means at each end of said container and also to form a second chamber within said container surrounding said cone-shaped members, means in the chamber means at one end of said container for introducing a gaseous medium thereto under pressure to agitate liquid adapted to be placed therein, means forming a discharge conduit from the chamber means at the opposite end of said container for conducting substantially dry foam therefrom, and vent flow passage means between the said chamber means and the said second chamber in the container that surrounds said chamber means.

5. A method of producing and delivering substantially dry stable foam to a region to be treated thereby comprising the steps of (a) establishing a liquid detergent body, (b) forcing the gaseous medium under pressure through said liquid detergent body to produce foam therefrom, (c) moving the foam so produced upwardly and compressing the foam during its upward movement

to break down the wet bubbles therein; (d) expanding the foam following the compression thereof to separate the foam into dry stable foam while permitting liquid entrained therein and wet foam to separate therefrom and return to the liquid detergent body, and (e) withdrawing the dry stable foam from the expanded foam and delivering it to the region to be treated.
